UNITED STATES PATENT OFFICE.

LOUIS L. DRIGGS, OF SHARON, PENNSYLVANIA, ASSIGNOR TO ORVILLE C. ALLEN, OF DETROIT, MICHIGAN.

SEMI-AUTOMATIC GUN.

996,569.

Specification of Letters Patent. Patented June 27, 1911.

Application filed April 13, 1906. Serial No. 311,537.

To all whom it may concern:

Be it known that I, LOUIS L. DRIGGS, a citizen of the United States, residing at Sharon, in the county of Mercer and State 5 of Pennsylvania, have invented certain new and useful Improvements in Semi-Automatic Guns; and I do hereby declare the following to be a full, clear, and exact description of the invention, such as will enable others skilled in the art to which it 10 pertains to make and use the same.

My invention relates to improvements in semi-automatic guns, and it consists in providing certain simplified apparatus for operating the breech mechanism of the gun, either by hand or by the stored up energy 15 of a spring operated on counter recoil, and in certain means for confining the operation of the apparatus either to the semi-automatic operation or to hand operation.

My invention also consists in certain other novel features and combinations and arrangements of parts as will be hereinafter described and claimed.

Reference is had to the accompanying drawings in which the same parts are indicated by the same letters throughout the several views.

Figure 1 is a side elevation of the breech 30 of the gun, parts being shown in section. Fig. 2 is a rear elevation of the breech of the gun, parts being omitted for the sake of clearness in the drawings. Fig. 3 shows a transverse section through a portion of 35 the mount and shows the operating and locking cams in engagement with the arm on the main bolt. Fig. 4 shows a section along the line 4—4 of Fig. 3, looking in the direction of the arrows. Figs. 5, 6, 7, 8, and 40 9 show diagrammatically the engagement of the operating cam with the arms carried by the main bolt.

A represents the gun body provided with the breech A' adapted to receive a reciprocating block A°. This gun body is provided with a downwardly projecting lug A², in which the main bolt D is journaled. The gun A recoils in the cradle B, which carries the recoil cylinders B'. These recoil 50 cylinders have the usual pistons, not shown, connected to the rods C, which rods are screw threaded as at c to engage interior

threads in the hollow screw C'. The exterior screw threads of this screw C' engage in the lug A². The hollow screw C' is 55 turned by means of the squared head c', and c² and c³ are lock nuts. By this arrangement, the piston rods C are adjustably connected to the lug A², and the compression of the return springs C⁴ in the recoil 60 cylinders B' may be adjusted, as desired. The breech block A° is operated by mechanism controlled by the main bolt D, which bolt may be turned either by the handle E, or by the semi-automatic attachment that 65 will now be described.

The details of the hand operating device may be of any suitable or well known type, such, for instance, as that described in the patent to William H. Driggs and V. C. 70 Tasker, No. 625,326, granted May 23, 1899.

Suitable extractors are provided, not only for extracting the empty cartridge case after firing the gun, but also for locking the breech in the open position until the said 75 extractors are tripped, as in loading the gun. Said extractors are well known in the art, and are shown, for instance, in the Driggs and Tasker patent referred to, and not being a part of my present invention 80 will not be described herein.

In order to operate the gun by the energy of the recoil, I provide a semi-automatic attachment, the parts of which for convenience of arrangement are distributed on opposite sides of the gun. On the right hand side of the gun I have shown the spring and the parts connected thereto for restoring the breech block to the closed position, and on the opposite side of the gun I have shown the yielding cam arrangement whereby the gun is allowed to recoil freely with the breech closed, and whereby the breech is opened on counter recoil, and whereby the breech mechanism may be locked against 95 hand operation, or the semi-automatic attachment may be thrown out of action, all of which will be hereinafter described.

Referring to Figs. 1 and 2, F represents 100 a short arm on the bolt D, which arm F engages a hook G connected by means of the chain G', to the hook g² on the end of the piston rod G². This piston rod carries a piston G³ loosely mounted in the cylinder

H, which is secured to the gun body, as by means of the dove-tail arrangement h , indicated in dotted lines in Fig. 2. Between this piston G³ and the end h' of the cylinder 5 H, the spring I is held under compression. The compression on the spring is adjusted by means of the clamp nuts g' , and the washer g , which are mounted on the screw threaded end g^3 of the rod G². The forward end of this cylinder H is open, so that a wrench may be inserted, and these lock nuts g' may be set up or eased off, as may be desired. The compression of this spring I should be so adjusted that this spring will 15 be able to restore the breech mechanism to the closed position when the said mechanism is released by the cam attachment on the opposite side of the gun. This cam attachment comprises two features, first a cam 20 block having engaging and locking arms, and, second, a block carried by the main bolt having arms with projections adapted to engage the cam members.

Referring now to Figs. 3 to 9, K represents a block carried by the main bolt D, which has two arms. The longer arm carries a roller K², and the shorter arm K' carries a lug k with an engaging face k' , which lug projects outwardly beyond the 25 outer edge of the roller K², as shown most clearly in Fig. 3. This lug k has a curved face k' , shown in dotted lines in Figs. 5 to 9. M represents a cam block, which is provided with two lugs M' and M². The shorter 30 lug M' is provided with a curved holding face m' adapted to engage the face k' on the arm K', while the longer and larger lug M² projects outward beyond the face of the lug M', so as to engage the roller K². This 35 lug M² has two engaging faces m^2 and m^3 , and a straight shoulder m^4 adapted to engage some part of the gun mount carried by the cradle when the lug M² is subjected to the pressure occasioned by the opening of 40 the breech mechanism. This holding shoulder m^4 is normally held in engagement with the corresponding face of the bar B³ fast to the cradle B, by means of the coil spring N, which is fast at one end to the block M, 45 and the other end to the bar B³, so that the said cam block may be rotated in one direction against the force of this spring, but is held against rotation in the opposite direction by the rigid engagement of the 50 shoulder m^4 , and the bar B³, as just described. It will be noted that the engaging face or shoulder of the bar B³ carried by the cradle is perpendicular to the line of 55 travel of the gun, so that there is no possibility of the cam rocking in the reverse direction when struck by the roller K² on counter recoil. The said cam block is shown as journaled in a socket B⁰ in the boss B⁴ secured to the bar B³. I provide an arrangement for throwing the semi-automatic at-

attachment into and out of operation, which comprises a cylindrical cover P knurled on its outside for convenience of manipulation, as shown in Fig. 2, and this cover is provided with a tongue P', which is provided with a flange sector p, which passes into the notch m^0 in the cam block, and engages in the segmental recess beneath the lip m , thus forming a bayonet joint. The end of this recess is indicated at m^x in Fig. 4, and the flange sector p engages the end of this recess when the parts are in the assembled position, as indicated in Figs. 3 and 4.

The cover P is provided with an annular recess n^0 between the tongue P' and the outer flange P², see Fig. 3, into which project the parts b^4 and m of the boss B⁴, and the block M respectively. The cover P, and with it the cam block M, may be held in either the operative or the inoperative position by means of the plunger Q, which is normally pressed inward by the spring Q' mounted in the casing Q² secured to the cover P. This plunger passes through the flange P² of the cover, and engages in one or the other of the notches b' or b^2 in the boss B⁴. When the parts are in the position for semi-automatic operation the spring plunger Q engages in the notch b' , as shown in Fig. 4, but by pulling the plunger out of the notch and rotating the cover P, and with it the cam block M, until this spring plunger snaps into the notch b^2 , the semi-automatic attachment may be thrown out of operation and the gun may be operated by hand only, as will be hereinafter described.

Assuming the parts to be in the position shown in Figs. 1, 2, and 5, and assuming the gun to be fired, the gun will recoil in the direction of the arrow indicated in Fig. 5, causing the bolt D to move across the cam block. The first movement of the bolt will cause the engaging face k' to clear the locking lug m' on the cam block. Shortly thereafter, the roller K² will strike the lug M² rotating the cam block backward against the action of its spring, the parts then assuming the position indicated in Fig. 6. After the roller K² passes clear of the lug M², the spring N will snap the cam back to the initial position, and the gun keeps on recoiling. As the gun comes forward again on counter recoil, the roller K² will strike the opposite face m^3 of the lug M², and will roll down this curved face, the cam block being rigidly held against motion in this direction, and the parts will assume the position shown in Fig. 7. This will cause the bolt D to open the breech mechanism, and this mechanism will be held in the open position by the extractor engagement, not shown, but already described, as well known in the art. After the roller K² has passed clear of the lug M², being the position immediately following that indicated in Fig. 7,

there will be no engagement whatever between the block K and the lugs M' and M², and the spring I would rock the bolt D back to the position for closing the breech were it 5 not for the engagement of the extractors with the breech block, as already described. Now when the extractors are tripped, as by the insertion of a fresh cartridge case, the spring I rocks the bolt D back to the position 10 for closing the breech, which is indicated in Fig. 5. Before reaching this position, however, the lug k¹ strikes the lug M', rocking the cam block to the position shown in Fig. 8, after which the face k' of the lug 15 k passes behind the face m' of the lug M', and the spring N then snaps the cam block back to the position shown in Fig. 5. When in this position, it will be evident that it will be impossible to turn the bolt D for 20 opening the breech by hand, and therefore the gun cannot be hand operated while the semi-automatic attachment is in engagement.

To throw the semi-automatic attachment 5 out of engagement, it will only be necessary to pull out the spring plunger Q, see Fig. 4, and then rotate the cam block until the plunger Q snaps into the notch b². This position of the cam block when thrown out 30 of engagement is illustrated in Fig. 9. When the parts are in this position, the gun can move on recoil and on counter recoil without any part of the block K striking any part of the cam block M.

35 Thus it will be seen that the semi-automatic attachment may be readily thrown into and out of engagement, that the gun cannot be operated by hand while the semi-automatic attachment is on, and that the 40 cam block may be readily applied to or removed from the gun by disengaging the cap P and drawing the cam block inward toward the gun, out of engagement with the recess B on the arm B³. Furthermore, the semi-automatic attachment is located out of the 45 way, and is more or less protected by the contiguous parts of the gun and mount. Furthermore, the breech actuating spring is inclosed in a protective casing, and at the 50 same time may be readily adjusted, when desired. Furthermore, this specific arrangement of recoil cylinders and pistons obviates the necessity of any band on the gun for the attachment thereto of the piston rods, the lug already provided as a bearing 55 for the main bolt being made use of for this purpose. This and the various other advantages of the herein described improved and simplified structure will be evident to 60 any one skilled in the art.

It will be obvious that various modifications might be made that could be used without departing from the spirit of my invention.

65 Having thus described my invention, what

I claim as new and desire to secure by Letters Patent of the United States, is:—

1. In a semi-automatic gun, the combination with the gun body and cradle, of one or more recoil cylinders and pistons connecting 70 said gun body and said cradle, a return spring mounted in each cylinder for restoring the gun to the initial position, a main bolt journaled beneath the breech of the gun, breech mechanism operated by said main bolt, a hand lever for rotating said main bolt, a lug on said main bolt for operating same automatically, a cylinder rigidly attached to said gun, a piston, piston rod and spring all recoiling with the gun, 75 mounted in said cylinder, a flexible connection between said piston rod and said lug on the main bolt, an arm on the opposite end of said main bolt, and a cam attached to a part of the cradle and adapted to yield when struck by said arm on recoil and to engage said arm and rock the same as the gun goes forward on counter-recoil, substantially as described.

2. In a semi-automatic gun, the combination with the gun body and cradle, of one or more recoil cylinders and pistons connecting 80 said gun body and said cradle, a return spring mounted in each cylinder for restoring the gun to the initial position, a main bolt journaled beneath the breech of the gun, breech mechanism operated by said main bolt, a hand lever for rotating said main bolt, a lug on said main bolt for operating same automatically, a cylinder rigidly 85 attached to said gun and open at its forward end, a piston, piston rod, and spring mounted in said cylinder all recoiling with the gun, with means for adjusting the position of the piston relative to the piston rod and thus adjusting the compression of said spring, a flexible connection between said piston rod and said lug on the main bolt, an arm on the opposite end of said main bolt, and a cam attached to a part of said cradle 90 and adapted to yield when struck by said arm on recoil and to engage said arm and rock the same as the gun goes forward on counter-recoil, substantially as described.

3. In a semi-automatic gun, the combination with the gun body having a downwardly projecting lug, and the cradle, of one or more recoil cylinders and pistons connecting 95 said lug on the gun body and said cradle, a return spring mounted in each cylinder for restoring the gun to the initial position, a main bolt journaled in said lug beneath the breech of the gun, breech mechanism operated by said main bolt, a hand lever for rotating said main bolt, a lug on said main bolt for operating same automatically, a cylinder rigidly attached to said gun, a piston, piston rod and spring, mounted in said cylinder all recoiling with the gun, a flexible 100 connection between said piston rod and

said lug on the main bolt, an arm on the opposite end of said main bolt, and a cam attached to a part of the cradle and adapted to yield when struck by said arm on recoil 5 and to engage said arm and rock the same as the gun goes forward on counter-recoil, substantially as described.

4. In a semi-automatic gun, the combination with the gun body having a downwardly projecting lug, and the cradle, of one or more recoil cylinders and pistons connecting said lug on the gun body and said cradle, a return spring mounted in each cylinder for restoring the gun to the initial 10 position, a main bolt journaled in said lug beneath the breech of the gun, breech mechanism operated by said bolt, a hand lever for rotating said main bolt, a lug on said main bolt for operating same automatically, a cylinder rigidly attached to said gun and open at its forward end, a piston rod and spring mounted in said cylinder all recoiling with the gun, with means for adjusting the position of the piston relative to the 15 piston rod and thus adjusting the compression of said spring, a flexible connection between said piston rod and said lug on the main bolt, an arm on the opposite end of said main bolt, and a cam attached to a part of said cradle and adapted to yield when struck by said arm on recoil and to engage said arm and rock the same as the gun goes forward 20 on counter-recoil, substantially as described.

5. In a semi-automatic gun, the combination with the gun body and cradle, of one or more recoil cylinders and pistons connecting said gun body and said cradle, a return spring mounted in each cylinder for restoring 25 the gun to the initial position, a main bolt journaled beneath the breech of the gun, breech mechanism operated by said main bolt, a lug on said main bolt for operating same automatically, a cylinder rigidly attached to said gun, a piston, piston rod and spring mounted in said cylinder and all recoiling with the gun, a flexible connection between said piston rod and said lug on the 30 main bolt, a cam arm on said main bolt, and a cam attached to a part of said cradle and adapted to yield when struck by said arm on recoil and to engage said arm and rock the same as the gun goes forward on counter-recoil, substantially as described.

6. In a semi-automatic gun, the combination with the gun body and cradle, of one or more recoil cylinders and pistons connecting said gun body and said cradle, a return 35 spring mounted in each cylinder for restoring the gun to the initial position, a main bolt journaled beneath the breech of the gun, breech mechanism operated by said main bolt, a hand lever for rotating said main bolt, a lug on said main bolt for operating 40 same automatically, a cylinder rigidly attached to said gun, and open at its forward end, a piston, piston rod and spring mounted in said cylinder and all recoiling with the gun, with means for adjusting the position 45 of the piston relative to the piston rod and thus adjusting the compression of said spring, a flexible connection between said piston rod and said lug on the main bolt, an arm on the opposite end of said main bolt, a cam block pivotally attached to a part of said cradle and provided with an engaging shoulder adapted to hold the cam against rotation when struck on counter-recoil, and a coil spring surrounding said cam block and adapted to yield when the cam is struck by said arm on recoil, substantially as described.

7. In a semi-automatic gun, the combination with the gun body and cradle, of one or more recoil cylinders and pistons connecting said gun body and said cradle, a return spring mounted in each cylinder for restoring the gun to the initial position, a main bolt journaled beneath the breech of the gun, breech mechanism operated by said main bolt, a hand lever for rotating said main bolt, a lug on said main bolt for operating same automatically, a cylinder rigidly attached to said gun, a piston, piston rod and spring mounted in said cylinder and all recoiling with the gun, the said piston rod being screw 70 threaded on its forward portion, with lock nuts for adjusting the position of the piston relative to the piston rod and thus adjusting the compression of said spring, a flexible connection between said piston rod and said lug on the main bolt, a cam arm on said main bolt, and a cam attached to a part of said cradle and adapted to yield when struck by said arm on recoil and to engage said arm and rock the same as the gun goes forward 75 on counter-recoil, substantially as described.

8. In a semi-automatic gun, the combination with the gun body and cradle, of one or more recoil cylinders and pistons connecting said gun body and said cradle, a return spring mounted in each cylinder for restoring the gun to the initial position, a main bolt journaled beneath the breech of the gun, breech mechanism operated by said main bolt, a hand lever for rotating said main bolt, a lug on said main bolt for operating same automatically, a cylinder rigidly attached to said gun, a piston, piston rod and spring mounted in said cylinder and all recoiling with the gun, a flexible connection between said piston rod and said lug on the main bolt, an arm on the opposite end of said main bolt, a cam block pivotally attached to a part of said cradle and provided with an engaging shoulder adapted to hold the cam against rotation when struck on counter-recoil, and a coil spring surrounding said cam block and adapted to yield when the cam is struck by said arm on recoil, substantially as described.

9. In a semi-automatic gun, the combination with the gun body and cradle, of one or more recoil cylinders and pistons connecting said gun body and said cradle, a return spring mounted in each cylinder for restoring the gun to the initial position, a main bolt journaled beneath the breech of the gun, breech mechanism operated by said main bolt, a hand lever for rotating said main bolt, a lug on said main bolt for operating same automatically, a cylinder rigidly attached to said gun, and open at its forward end, a piston, piston rod and spring mounted in said cylinder and all recoiling with the gun, with means for adjusting the position of the piston relative to the piston rod and thus adjusting the compression of said spring, a flexible connection between said piston rod and said lug on the main bolt, an arm on the opposite end of said main bolt, a cam block pivotally attached to a part of said cradle and provided with an engaging shoulder adapted to hold the cam against rotation when struck on counter-recoil, and a coil spring surrounding said cam block and 100

105

110

115

120

125

130

adapted to yield when struck by said arm on recoil and to restore said cam to the position for engaging said arm as the gun goes forward on counter-recoil, substantially as described.

9. In a semi-automatic gun, the combination with the gun body and cradle, of one or more recoil cylinders and pistons connecting said gun body and said cradle, a return 10 spring mounted in each cylinder for restoring the gun to the initial position, a main bolt journaled at the breech of the gun, breech mechanism operated by said main bolt, means for rotating said main bolt by

15 hand, a lug on said main bolt for operating same automatically, a cylinder rigidly attached to said gun, a piston, piston rod and spring, mounted in said cylinder and all recoiling with the gun, means for connecting 20 said piston rod and said lug on the main bolt, an arm on the main bolt, and a cam attached to a part of the cradle and adapted to yield when struck by said arm on recoil and to engage said arm and rock the same as 25 the gun goes forward on counter-recoil, substantially as described.

10. In a semi-automatic gun, the combination with the gun body and cradle, of one or 30 more recoil cylinders and pistons connecting said gun body and said cradle, a return spring mounted in each cylinder for restoring the gun to the initial position, a main bolt journaled at the breech of the gun, breech mechanism operated by said main 35 bolt, means for rotating said main bolt by hand, a lug on said main bolt for operating same automatically, a cylinder rigidly attached to said gun and open at its forward end, a piston, piston rod and spring, mounted in said cylinder and all recoiling with the gun, with means for adjusting the position of the piston relative to the piston rod and thus adjusting the compression of said 40 spring, means for connecting said piston rod and said lug on the main bolt, an arm on main bolt, and a cam attached to a part of said cradle and adapted to yield when struck by said arm on recoil and to engage said arm and rock the same as the gun goes 45 forward on counter-recoil, substantially as described.

11. In a semi-automatic gun, the combination with the gun body and cradle, of one or 50 more recoil cylinders and pistons connecting said gun body and said cradle, a return spring mounted in each cylinder for restoring the gun to the initial position, a main bolt journaled at the breech of the gun, breech mechanism operated by said main 55 bolt, means for rotating said main bolt by hand, a lug on said main bolt for operating same automatically, a cylinder rigidly attached to said gun and open at its forward end, a piston, piston rod and spring, mounted in said cylinder and all recoiling with the

gun, the forward portion of said piston rod being screw threaded, a nut on said screw threaded portion of said piston rod, means for connecting said piston rod and said lug on the main bolt, an arm on main bolt, and 70 a cam attached to a part of said cradle and adapted to yield when struck by said arm on recoil and to engage said arm and rock the same as the gun goes forward on counter-recoil, substantially as described. 75

12. In a semi-automatic gun, the combination with the gun body and cradle, of one or more recoil cylinders and pistons connecting said gun body and said cradle, a return spring mounted in each cylinder for restoring the gun to the initial position, a main bolt journaled to the breech of the gun, breech mechanism operated by said main bolt, a lug on said main bolt for operating same automatically, a cylinder rigidly attached to said gun, a piston, piston rod and a spring under compression, all mounted in said cylinder and all recoiling with the gun, means for varying the compression of said spring, a flexible connection between 80 said piston and said lug on the main bolt, and mechanism operated on counter-recoil for opening the breech against the action of said spring, substantially as described. 85

13. In a semi-automatic gun, the combination with the gun body and cradle, of one or more recoil cylinders and pistons connecting said gun body and said cradle, a return spring mounted in each cylinder for restoring the gun to the initial position, a main bolt journaled to the breech of the gun, breech mechanism operated by said main bolt, a lug on said main bolt for operating same automatically, a cylinder rigidly attached to said gun and open at its forward end, a piston, a screw threaded piston rod, and a spring under compression, all mounted in said cylinder and all recoiling with the gun, with lock nuts for adjusting the position of the piston relative to the piston rod and thus adjusting the compression of said 100 spring, means for connecting said piston rod and said lug on the main bolt, and mechanism operated on counter-recoil for opening the breech against the action of said spring, substantially as described. 105

14. In a semi-automatic gun, the combination with the gun body and cradle, of one or more recoil cylinders and pistons connecting said gun body and said cradle, a return spring mounted in each cylinder for restoring the gun to the initial position, a main bolt journaled at the breech of the gun, breech mechanism operated by said main 110 bolt, means for rotating said main bolt by hand, a lug on said main bolt for operating same automatically, an operating spring normally under compression connected to said lug, a casing exterior to and separate 115 from the recoil cylinder detachably con- 120

125

130

nected to the gun and containing said spring, an arm on the opposite end of said main bolt, and mechanism operated on counter-recoil for opening the breech against the action of said spring, and a cam attached to a part of the cradle and adapted to yield when struck by said arm on recoil and to abut against a rigid face of the cradle and engage said arm and rock the same as the gun goes forward on counter-recoil, with means for throwing said cam into and out of engagement, substantially as described.

15. In a semi-automatic gun, the combination with the gun body and cradle, of one or more recoil cylinders and pistons connecting said gun body and said cradle, a return spring mounted in each cylinder for restoring the gun to the initial position, a main bolt journaled at the breech of the gun, breech mechanism operated by said main bolt, a means for rotating said main bolt by hand, a lug on said main bolt for operating same automatically, an operating spring normally under compression connected to said lug, a casing exterior to and separate from the recoil cylinder detachably connected to the gun and containing said spring, an arm on the opposite end of said main bolt, and mechanism operated on counter-recoil for opening the breech against the action of said spring, and a cam attached to a part of the cradle and adapted to yield when struck by said arm on recoil and to abut against the rigid face of the cradle and to rock the said arm as the gun goes forward on counter-recoil, substantially as described.

16. In a breech loading gun, the combination with a main bolt for operating the breech mechanism, and a cam arrangement for rocking this bolt on counter recoil, of a casing detachably secured to the gun body exterior to the recoil cylinder, a rod mounted in said casing, a collar mounted on said rod and loosely fitting in said casing, means for adjusting the position of said collar on said rod, a coil spring mounted on said rod and held under compression between said collar and said casing, and means for connecting said rod to an arm on said main bolt, said coil spring, rod and casing recoiling with the gun, substantially as described.

17. In a breech loading gun, the combination with a main bolt for operating the breech mechanism, and a cam arrangement for rocking this bolt on counter recoil, of a cylindrical casing open at one end and secured to the gun body, a rod mounted in said casing and screw threaded along a portion thereof, a collar mounted on said rod and loosely fitting in said casing, lock nuts for adjusting the position of said collar on said rod, a coil spring mounted on said rod and held under compression between said collar and said casing, and means for connecting said rod to an arm on said main

bolt, said coil-spring, rod, and casing recoiling with the gun, substantially as described.

18. In a breech loading gun, the combination with a main bolt for operating the breech mechanism, and a cam arrangement for rocking this bolt on counter recoil of a cylindrical casing open at one end and secured to the gun body, a rod mounted in said casing and screw threaded along a portion thereof, a collar mounted on said rod and loosely fitting in said casing, lock nuts for adjusting the position of said collar on said rod, a coil spring mounted on said rod and held under compression between said collar and said casing, and a flexible connection between said rod and an arm on said main bolt, said coil-spring, rod, and casing recoiling with the gun, substantially as described. 75

19. In a semi-automatic gun, the combination with the gun and cradle, the latter having a shoulder perpendicular to the line of travel of the gun, of the main bolt adapted to rock on its axis, of an arm carried by said main bolt provided with a lug or roller projecting therefrom parallel to the axis of the main bolt, a rotary cam block mounted in the cradle and provided with a cam adapted to engage said lug or roller and also provided with a shoulder adapted to engage the corresponding shoulder on the cradle and to hold the cam block against rotation in one direction, and a coil spring mounted on said cam block and adapted to normally hold said shoulders in engagement, but to yield against pressure in the reverse direction, substantially as described. 90

20. In a semi-automatic gun, the combination with the gun and cradle, the latter having a shoulder perpendicular to the line of travel of the gun, of the main bolt adapted to rock on its axis, of an arm carried by said main bolt provided with a lug or roller projecting therefrom parallel to the axis of the main bolt, a rotary cam block mounted in the cradle and provided with a cam adapted to engage said lug or roller and also provided with a shoulder adapted to engage the corresponding shoulder on the cradle and to hold the cam block against rotation in one direction, and a coil spring mounted on said cam block and adapted to normally hold said shoulders in engagement, but to yield against pressure in the reverse direction, 100 substantially as described. 110

21. In a semi-automatic gun, the combination with the gun and cradle, the latter having a shoulder perpendicular to the line of travel of the gun, of the main bolt adapted to rock on its axis, of an arm carried by said main bolt provided with a lug or roller, 115 120 125 130

- projecting therefrom parallel to the axis of the main bolt, a rotary cam block mounted in the cradle and provided with a cam adapted to engage said lug or roller and also provided with a shoulder adapted to engage the corresponding shoulder on the cradle and to hold the cam block against rotation in one direction, and a coil spring mounted on said cam block and adapted to normally hold said shoulders in engagement, but to yield against pressure in the reverse direction, with a spring latch adapted to lock said cam block in the operative or inoperative position as may be desired, substantially as described.
22. In a semi-automatic gun, the combination with the gun and cradle, the latter having a shoulder perpendicular to the line of travel of the gun, of the main bolt adapted to rock on its axis, of an arm carried by said main bolt provided with a lug or roller projecting therefrom parallel to the axis of the main bolt, and a locking arm also carried by said main bolt, a rotary cam block mounted in the cradle and provided with a cam adapted to engage said lug or roller, and a locking lug to engage said locking arm, and also provided with a shoulder adapted to engage the corresponding shoulder on the cradle and to hold the cam block against rotation in one direction, and a coil spring mounted on said cam block and adapted to normally hold said shoulders in engagement, but to yield against pressure in the reverse direction, with a spring latch adapted to lock said cam block in the operative or inoperative position as may be desired, substantially as described.
23. In a semi-automatic gun, the combination with a gun and cradle, the latter having a shoulder perpendicular to the line of travel of the gun, of the main bolt adapted to rock on its axis, of an arm carried by said main bolt provided with a lug or roller projecting therefrom parallel to the axis of the main bolt, and a locking arm also carried by said main bolt, a rotary cam block mounted in the cradle and provided with a cam adapted to engage said lug or roller and a locking lug to engage said locking arm, and also provided with a shoulder adapted to engage the corresponding shoulder on the cradle and to hold the cam block against rotation in one direction, and a coil spring mounted on said cam block and adapted to normally hold said shoulders in engagement, but to yield against pressure in the reverse direction, with means for locking said cam block either in the operative or inoperative position as may be desired, substantially as described.
24. In a semi-automatic gun, the combination with the gun and cradle, the latter having a shoulder perpendicular to the line of travel of the gun, of the main bolt adapted to rock on its axis, of an arm carried by said main bolt provided with a lug or roller projecting therefrom parallel to the axis of the main bolt, and a locking arm also carried by said main bolt, a rotary cam block mounted in the cradle and provided with a cam adapted to engage said lug or roller, and a locking lug to engage said locking arm, and also provided with a shoulder adapted to engage the corresponding shoulder on the cradle and to hold the cam block against rotation in one direction, and a coil spring mounted on said cam block and adapted to normally hold said shoulders in engagement, but to yield against pressure in the reverse direction, with a spring latch adapted to lock said cam block in the operative or inoperative position as may be desired, substantially as described.
25. In a breech loading gun, the combination with a main bolt for operating the breech mechanism, and a cam arrangement for rocking this bolt on counter recoil, of a cylindrical casing open at one end and secured to the gun body, a rod mounted in said casing, a collar mounted on said rod, a coil spring mounted on said rod and held under compression between said collar and said casing, means for varying the compression of said spring, and means for connecting said rod to an arm on said main bolt, said casing, coil-spring, and rod all recoiling with the gun, substantially as described.
26. In a breech loading gun, the combination with a main bolt for operating the breech mechanism, and a cam arrangement for rocking this bolt on counter recoil, of a cylindrical casing open at one end and secured to the gun body, a rod mounted in said casing and screw threaded along a portion thereof, a collar mounted on said rod and loosely fitting in said casing, a coil spring mounted on said rod and held under compression between said collar and said casing, a nut for compressing said spring, and means for connecting said rod to an arm on said main bolt, said casing, coil-spring, and rod all recoiling with the gun, substantially as described.
27. In a semi-automatic gun, the combination with the gun body and cradle, of one or more recoil cylinders, a main bolt journaled to the breech of the gun, breech mechanism operated by said main bolt, a lug on said main bolt for operating same automatically, a cylinder rigidly attached to said gun exterior to the recoil cylinder; a piston, piston rod and a spring under compression, all mounted in said cylinder and all recoiling with the gun, means for varying the compression of said spring, a connection between said piston and said lug on the main bolt, and mechanism operated on counter recoil for opening the breech against the action of said spring, substantially as described.
28. In a semi-automatic gun, the combination with the gun body and cradle, of one or more recoil cylinders, a main bolt journaled to the breech of the gun, breech mechanism operated by said main bolt, a lug on said main bolt for operating same automatically, a cylinder rigidly attached to said gun exterior to the recoil cylinder; a piston, piston rod and a spring under compression, all mounted in said cylinder and all recoiling with the gun, means for varying the compression of said spring, a connection between said piston and said lug on the main bolt, and mechanism operated on counter recoil for opening the breech against the action of said spring, substantially as described.

nation with the gun body and cradle, of one or more recoil cylinders and a main bolt journaled to the breech of the gun, breech mechanism operated by said main bolt, a lug on said main bolt for operating same automatically, a cylinder rigidly attached to said gun and open at its forward end, a piston, a screw threaded piston rod, and a spring under compression, all mounted in 10 said cylinder and all recoiling with the gun, a nut, for adjusting the position of the piston relative to the piston rod and thus adjusting the compression of said spring, means for connecting said piston rod and 15 said lug on the main bolt, and mechanism operated on counter-recoil for opening the breech against the action of said spring, substantially as described.

29. In a breech loading gun, the combination with a main bolt for operating the breech mechanism, and a cam arrangement for rocking this bolt on counter recoil, of a cylindrical casing open at one end and secured to the gun body, a rod mounted in 25 said casing and screw threaded along a portion thereof, a collar mounted on said rod and loosely fitting in said casing, a nut for adjusting the position of said collar on said rod, a coil spring mounted on said rod and 30 held under compression between said collar and said casing, and means for connecting said rod to an arm on said main bolt, said coil spring, rod, and casing recoiling with the gun, substantially as described.

30. In a breech loading gun, the combination with a main bolt for operating the breech mechanism, and a cam arrangement for rocking this bolt on counter recoil, of a cylindrical casing open at one end and secured to the gun body, a rod mounted in 40 said casing and screw threaded along a portion thereof, a collar mounted on said rod and loosely fitting in said casing, a nut for adjusting the position of said collar on said rod, a coil spring mounted on said rod and held under compression between said collar and said casing, and a connection between said rod and an arm on said main bolt, said coil spring, rod, and casing recoiling 45 with the gun, substantially as described.

31. In a semi-automatic gun, the combination with the gun body and cradle, of one or more recoil cylinders, a main bolt journaled to the breech of the gun, breech mechanism operated by said main bolt, means on 55 said main bolt for operating same automatically, a cylinder rigidly attached to said gun exterior to the recoil cylinder; a piston,

piston rod and a spring under compression, all mounted in said cylinder and all recoiling with the gun, a connection between said piston and said main bolt, and mechanism operated on counter-recoil for opening the breech against the action of said spring, substantially as described. 60 65

32. In a semi-automatic gun, the combination with the gun body and cradle, of one or more recoil cylinders, a main bolt journaled to the breech of the gun, breech mechanism operated by said main bolt, means on 70 said main bolt for operating same automatically, a cylinder rigidly attached to said gun exterior to the recoil cylinder; a piston, piston rod and a spring under compression, all mounted in said cylinder and all recoiling 75 with the gun, means for varying the compression of said spring, a connection between said piston and main bolt, and mechanism operated on counter-recoil for opening the breech against the action of said 80 spring, substantially as described.

33. In a breech loading gun, the combination with a main bolt for operating the breech mechanism, and a cam arrangement for rocking this bolt on counter recoil, of a 85 cylindrical casing detachably secured to the gun body exterior to the recoil cylinder, a rod mounted in said casing, a collar mounted on said rod and loosely fitting in said casing, means for adjusting the position of said collar on 90 said rod, a coil spring mounted on said rod and held under compression between said collar and said casing, and means for connecting said rod to a part on said main bolt, said coil spring, rod and casing recoiling 95 with the gun, substantially as described.

34. In a breech loading gun, the combination with a main bolt for operating the breech mechanism, and a cam arrangement for rocking this bolt on counter-recoil, of a 100 cylindrical casing open at one end and secured to the gun body, a rod mounted in said casing, a collar mounted on said rod, a coil spring mounted on said rod and held under compression between said collar and said casing, means for varying the compression of said spring, and means for connecting said rod to a part on said main bolt, said casing, coil - spring, and rod all recoiling 105 with the gun, substantially as described. 110

In testimony whereof, I affix my signature, in presence of two witnesses.

LOUIS L. DRIGGS.
